US00D829707S

(12) **United States Design Patent** (10) Patent No.: **US D829,707 S**
(45) Date of Patent: ** Oct. 2, 2018

(54) **COMPUTER LAPTOP ASSEMBLY**

(71) Applicant: **Intel Corporation**, Santa Clara, CA (US)

(72) Inventors: **William Tin**, Shenzhen (CN); **Chunlin Tony Bai**, Shenzhen (CN); **La Hung Richard Shih**, Shenzhen (CN); **Jie Gandalf Yan**, Shenzhen (CN)

(73) Assignee: **Intel Corporation**, Santa Clara, CA (US)

(**) Term: **15 Years**

(21) Appl. No.: **29/577,508**

(22) Filed: **Sep. 13, 2016**

(51) LOC (11) Cl. **14-02**

(52) U.S. Cl.

USPC **D14/315**; D14/327

(57) **CLAIM**

The ornamental design for a computer laptop assembly, as shown and described.

DESCRIPTION

FIG. 1 is an upper-rear perspective view of a computer laptop assembly, shown in a closed clamshell configuration; FIG. 2 is a lower-front perspective view thereof;

FIG. 3 is top view thereof;

FIG. 4 is a bottom view thereof;

FIG. 5 is a front view thereof;

FIG. 6 is a rear view thereof;

FIG. 7 is a right side thereof;

FIG. 8 is a left side thereof;

FIG. 9 is an upper-rear perspective view of the design of FIG. 1, shown in an opened clamshell configuration;

FIG. 10 is a lower-front perspective view thereof;

FIG. 11 is a top view thereof;

FIG. 12 is bottom view thereof;

FIG. 13 is a front view thereof;

FIG. 14 is a rear view thereof;

FIG. 15 is a right side view thereof; and,

FIG. 16 is a left side view thereof.

Broken lines in the drawings depict portions of the computer laptop assembly that form no part of the claimed design.

1 Claim, 11 Drawing Sheets
